CLAIM

The ornamental design for a cleaner apparatus for a phase change ink printer, as shown and described.

DESCRIPTION

FIG. 1 is a perspective view of a cleaner apparatus for a phase change ink printer in accordance with the present invention;

FIG. 2 is a front view thereof;

FIG. 3 is a right side view thereof;

FIG. 4 is a rear view thereof;

FIG. 5 is a left side view thereof;

FIG. 6 is a top plan view thereof; and,

FIG. 7 is a bottom plan view thereof.

The broken line showing of portions of the cleaner apparatus are included for the purpose of illustrating environmental structure and form no part of the claimed design.
